AMÉLIE ADÈLE LONGUEMARE, FERNAND LONGUEMARE, AND GEORGES LONGUEMARE, OF PARIS, FRANCE; SAID FERNAND LONGUEMARE AND GEORGES LONGUEMARE ASSIGNORS TO SAID AMÉLIE ADÈLE LONGUEMARE.

CARBURETER FOR HYDROCARBON-ENGINES.

No. 820,583.

Specification of Letters Patent.

Patented May 15, 1906.

Application filed March 4, 1904. Serial No. 196,633.

To all whom it may concern:-

Be it known that we, AMÉLIE ADÈLE LONGUEMARE, FERNAND LONGUEMARE, and GEORGES LONGUEMARE, citizens of the Republic of France, and residents of Paris, France, have invented certain new and useful Improvements in Carbureters for Hydrocarbon-Engines, of which the following is a specification.

10 This invention relates to an apparatus for the automatic regulation of the total admission of air to a carbureter, said regulation being such that the opening of the orifice through which air is drawn in by the piston 15 of the engine is automatically increased or diminished according to the speed of the engine.

The accompanying drawing shows a partial section through the axis of a carbureter 20 provided with this regulating device, which chiefly consists of a bent tube or casing *a*, forming an extension of the orifices *b* for the admission of air into the carbureter. This pipe *a* is fixed in place in any suitable manner—such as, for instance, by means of a central rod *c*, arranged as an extension and below the center of the carbureter. This rod passes through the wall of the casing and receives a nut *d*, which holds the casing in the 30 desired position.

The horizontal mouth of the casing *a* is of rectangular, oval, or circular cross-section and is closed by a vertical shutter *e*, hinged at the top at *f* and preferably provided with 35 a weight *g* at the bottom. A screw *h* forms a stop against which the shutter *e* strikes when under the influence of its own weight it closes the mouth of the tube *a*.

When the engine is running slowly, there 40 is only a small suction of air in the tube *a*, so that the shutter *e* is opened only to a small extent. The resistance to opening offered by the weighted shutter *e* enables a sufficient depression to be produced in the carbureter 45 in order that the liquid may be drawn through the grooves of the atomizer and a suitable gaseous supply maintained. When, however, the engine is running very fast, the depression in the pipe *a* becomes stronger, 50 and the atmospheric air entering in larger

quantities through the tube *a* acts on the shutter *e* and maintains it open to a greater extent. The degree of opening of the tube *a* is thus automatically maintained in proportion to the speed of the engine or, rather, to 55 the quantity of the mixture drawn in. It must be pointed out that in case of use on a motor-car when the car is climbing a hill in the direction of the arrow the tube will be at an angle inclined upwardly and the shutter 60 will be the more strongly closed the greater the gradient. The result will be that the admission of air taking place with greater difficulty the piston will draw in a mixture richer in hydrocarbon. The reverse will take place 65 when the car is going downhill. In fact, the weight *g* of the shutter *e* will have the tendency to maintain the shutter slightly open, and consequently will facilitate idle movement of the piston without any effort on the 70 part of the latter during its suction period.

What we claim as our invention, and desire to secure by Letters Patent, is—

1. In an air-regulating device for carbureters for motor-vehicles, an air-inlet conduit for communicating with an air-passage in which the fuel-duct empties, in combination with a freely-suspended flap-valve weighted at its lower end in said conduit adapted to open in the direction of the motion of the vehicle, substantially as set forth. 75

2. In an air-regulating device for carbureters for motor-vehicles, an air-inlet conduit for communicating with an air-passage in which the fuel-duct empties, in combination with a freely-suspended flap-valve weighted at its lower end in said conduit adapted to open in the direction of the motion of the vehicle and a valve-stop, substantially as set forth. 85

In testimony whereof we have signed our names to this specification in the presence of two subscribing witnesses.

AMÉLIE ADÈLE LONGUEMARE.
FERNAND LONGUEMARE.
GEORGES LONGUEMARE.
